Primary Examiner — Marie D. Fast Horse*(74) Attorney, Agent, or Firm* — Holtz, Holtz & Volek PC(57) **CLAIM**

The ornamental design for an electronic calculator, as shown and described.

DESCRIPTION

FIG. 1 is a reduced-scale front, right side, bottom perspective view of an electronic calculator showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reduced-scale rear, left side, bottom perspective view thereof.
